UNITED STATES PATENT OFFICE.

LOUIS KOOPERSTEIN, OF NEW YORK, N. Y., ASSIGNOR TO WEST DISINFECTING COMPANY, OF NEW YORK, N. Y., A CORPORATION OF NEW YORK.

SOAP-DISPENSING APPARATUS.

Application filed April 7, 1925. Serial No. 21,281.

The object of the present invention is to provide soap dispensing apparatus adapted for mounting upon a wash bowl frame or cover in such manner that the supply of 5 soap is maintained in a container disposed under the surface of the wash bowl or the like, an ejection nozzle and an operating plunger being exposed above the bowl, the arrangement being such that upon detach- 10 ing the nozzle and removing a holding strap for the soap container, the entire device may be lowered and withdrawn from the wash bowl or like device.

Other objects of the invention are to pro- 15 vide a device of this character which shall be positive in its action, simple in construction, readily constructed and disassembled, etc. A further object of the invention is to provide ejection means of a type in which 20 the manually operated member is a plunger so formed, supported, and guided, that it cannot be operated by striking with the hand as in the case of the usual plunger-operated devices, which, when struck with a sudden 25 blow, will eject the soap with undue force so that it splatters.

The invention will be understood by reference to the accompanying drawings in which—

30 Figure 1 is a sectional elevation of an apparatus constructed in accordance with the invention and mounted in position;

Figure 2 is a front elevation of the same;

35 Figure 3 is a transverse section on the line 3—3, Figure 1;

Figure 4 is a plan view of the intake valve head and bowl valve, slightly enlarged.

Referring to Figure 1 of the drawings, A represents the horizontal portion of a 40 lavatory top or wash bowl which may be, for example, such as employed in Pullman cars. The soap container or receptacle is indicated at 1. It may be made of any suitable material, preferably of glass, and has 45 secured thereto a flanged neck 2 upon which is adapted to move a flanged collar 3, the interior face of the collar being threaded so as to engage the threads of a neck 4 depending from the nozzle head 5, the latter being provided with a nozzle 6.

50 Nozzle head 5 has rigidly secured thereto a tube 7 closed at its lower end by valve head 8 shown in detail in Figure 4. Valve head 8 is threaded upon the lower end of

tube 7. It is formed with a central aperture having a bevelled inner face, the aperture being normally closed by a ball 9. When suction is created within the tube, ball 9 is moved upwardly to permit the soap lying within container 1 to pass into tube 7. The ball is held in proper position within the valve head by means of a cage comprising the wires 10.

Within tube 7 is a piston 11, the piston being carried by a piston rod 12, which at its upper end is connected to a plunger 12^x, the plunger being provided with a central aperture or passageway normally closed by the threaded cap 13, the aperture communicat- 65 ing with a transverse duct 14 which is adapt- 70 ed to come in communication with the ports 15 formed in the side wall of the tube 12, whereby the container 1 may be supplied with soap. In other words, when cap 13 is removed and the plunger moved down- 75 ward a short distance to bring ports 14, 15 into communication, liquid soap may be poured into passageway 12 and thence into the container 1.

The plunger in its reciprocating move- 80 ments is held against turning and thus main- 85 tained in such position that duct 14 will always register with ports 15, by means of a guide pin 16, which enters guiding aper- 90 ture 17 in the nozzle head. The plunger is normally maintained in upper position by 95 means of spring 18 which at its lower end engages the inner flange or wall 19 of tube 7, and its upper end engages the plunger.

In tube 7 below the piston and above the ball valve, is a small outlet aperture com- 90 municating with a tube 20 of relatively small diameter, the said tube communicating with a duct 21, leading to the nozzle 6. The nozzle 6 may be secured to nozzle head 5 in any suitable manner. For example, it 95 may be threaded in the said nozzle head and thus readily removed therefrom when it is desired to remove the entire apparatus from the bowl A. Or, by unthreading collar 3, the container 1 may be detached from the 100 head 5 and the two units removed as separate units from the bowl or other device to which they are attached.

In Figure 1, I have shown the aperture in lavatory top or bowl A through which the piston head projects, protected by a ring 22 and to this ring is secured by rivets 23

or other suitable means a strap 24 by means of which the container, and the dispensing apparatus as a whole, is held in position upon bowl A.

5 In the operation of the device, the plunger B is pressed downwardly with the thumb or finger, which causes soap intermediate the piston 11 and the base of tube 7 to be ejected through small tube 20, duct 21 and 10 nozzle 6. When the plunger is released, spring 8 will serve to raise it to initial position, carrying upward the piston 11, and, by suction, raising ball 19 and filling the base of the tube 7 with soap, ready for the 15 next downward ejecting movement of the piston.

It will be understood that various modifications may be made in the form and arrangement of the elements illustrated in 20 the drawing without departing from the spirit of my invention, what I claim and desire to secure by Letters Patent being as follows:

25 1. A liquid soap dispensing device, comprising a nozzle head provided with a nozzle, the head being formed with a chamber having lateral guide walls, a hollow plunger mounted in said chamber and engaging the said walls, the plunger having a lateral 30 outlet, a tube supported by the nozzle head and adapted to receive the plunger, a piston carried by the plunger and movable within the tube, a soap inlet and a soap outlet in the tube, a passageway affording communication between the outlet and the nozzle, the tube being formed with an outlet 35 normally below the outlet of the plunger, the two outlets coming into register when the plunger is depressed.

40 2. A liquid soap dispensing device, comprising a nozzle head and nozzle, the head being formed with a chamber having lateral guide walls, a hollow plunger mounted in said chamber and engaging said walls, the 45 plunger being provided with a transverse outlet, a tube carried by said head and adapted to receive said plunger, the tube being provided with an outlet adapted to coact with the outlet of the plunger, a piston carried by the plunger and movable within the tube, a soap inlet and a soap outlet in the tube, and means permitting the

passage of soap from the outlet to the nozzle.

3. A liquid soap dispensing device, comprising a receptacle, a nozzle head and nozzle, and means for connecting the nozzle head and the receptacle, the head being formed with a chamber, a plunger mounted in said chamber for endwise movement, a tube, a piston operated by said plunger and movable within the tube, a passageway leading through the plunger and communicating with the receptacle whereby soap fed into the plunger may pass into the receptacle, a soap inlet and a soap outlet in the tube, and means permitting the passage of soap from said outlet to the nozzle. 55 60 65

4. A liquid soap dispensing device, comprising a nozzle head and nozzle, the head being formed with a chamber having lateral guide walls, a tube communicating with said chamber, a hollow plunger mounted in said chamber and projecting into the tube, the plunger having a lateral outlet duct 70 75 normally closed by the walls of the tube, an outlet duct in the tube, a spring normally holding the plunger so that its outlet duct is above the outlet duct of the tube, a piston operated by said plunger and movable within the tube, a soap inlet and outlet in the tube, and means permitting the passage of soap from said outlet to the nozzle. 80

5. A liquid soap device, comprising a nozzle head and nozzle, the head being formed with a chamber having lateral guide walls, a plunger mounted in said chamber and having endwise movement therein, a passageway formed in the plunger, said passageway being normally closed by a removable cap, a tube receiving said plunger and having an outlet passage adapted to communicate with the passageway of the plunger when the latter is given an endwise movement, a spring adapted to hold the plunger in upper position, a piston carried by the plunger and movable within the tube, a soap inlet and outlet in the tube and means for permitting the passage of soap from the outlet to the nozzle. 85 90 95 100

In testimony whereof, I have signed my name to this specification.

LOUIS KOOPERSTEIN.
